(57) **CLAIM**

The ornamental design for a holographic showcase, as shown and described.

DESCRIPTION

FIG. 1 is an isometric view of a first holographic showcase showing my new design;

FIG. 2 is a front view thereof;

FIG. 3 is a back view thereof;

FIG. 4 is a top view thereof;

FIG. 5 is a bottom view thereof;

FIG. 6 is a left side view thereof; and,

FIG. 7 is a right side view thereof.

The design includes light-transmissible material.
